UNITED STATES PATENT OFFICE.

CHARLES WIRTZ WAGNER, OF NEW YORK, N. Y.

LIQUID-FAUCET.

1,264,718.

Specification of Letters Patent. Patented Apr. 30, 1918.

Application filed October 10, 1917. Serial No. 195,836.

To all whom it may concern:

Be it known that I, CHARLES W. WAGNER, a citizen of the United States, and a resident of New York city, borough of Manhattan, 5 in the county of New York and State of New York, have invented a new and Improved Liquid-Faucet, of which the following is a full, clear, and exact description.

Among the principal objects which the 10 present invention has in view are, to provide a faucet which may be readily repaired or the wearing members of which may be easily replaced; to minimize the space occupied by the faucet; and to cheapen the cost of construction.

Drawings.

Figure 1 is a vertical section of a faucet constructed and arranged in accordance with 20 the present invention, the section being taken as on the line 1—1 in Fig. 2.

Fig. 2 is a cross section, the section being taken as on the line 2—2 in Fig. 1.

Fig. 3 is a vertical section of a faucet constructed and arranged in accordance with a modified form of the invention, the section being taken as on the line 3—3 in Fig. 4.

Fig. 4 is a cross section showing the modified form of the invention, the section being 30 taken as on the line 4—4 in Fig. 3.

Description.

As seen in the drawings, the faucet spout 9 is provided with a threaded head 10, the 35 face 11 whereof is level to form a valve seat for a cushion 12. The cushion 12 above mentioned is rigidly attached by any suitable form of fastening such as the screw 13, to a bridge 14. The bridge 14 is supported by a 40 screw-threaded tube. In the side of the tube 15 are formed openings 16. The cushion 12 may be constructed of any suitable material, that most generally used being a leather pad or washer.

The nozzle 17 has a delivery passage 18 and an enlarged body chamber, the interior whereof is provided with an internal thread 19. The thread 19 corresponds with the thread with which the head 10 is furnished. 45 For manipulating the nozzle 17, it is provided with handles 20 or other similar devices, permitting one to grasp the nozzle to turn the same.

In the operation of the faucet, it will be 55 understood that the nozzle 17 is turned on the thread 19 and head 10 until the pad 12 is

pressed firmly against the seat 11. The pressure applied is against the pressure of the water in the faucet 9 and the main water supply with which the said nozzle is connected. When desiring to permit the water to flow, the nozzle is retracted by reversing the operation on the screw thread until the pad 12 is released from its seat. Water then flows past the said pad under the bridge 14 60 through the openings 16 and tube 15. It is obvious that should the pad 12 become worn or parts connected therewith be broken, the nozzle may be easily and readily removed from the head 10 to permit the repair or replacement of the said pad or parts.

To prevent the nozzle 17 being retracted or removed accidentally from the head 10, a stop screw 21 is provided. The screw 21 is threaded in a lug 22 extending from the 75 barrel of the nozzle 17. As shown best in Fig. 3, the head 10 is shaped to form an abutment shoulder 23 at the upper and inner side thereof, which the screw 21 engages if the nozzle 17 is retracted sufficiently. It 80 will be understood that when the screw 21 engages the shoulder 23, a further retraction of the nozzle is prevented.

In the modified form shown in Figs. 3 and 4, a spider disk 24 is provided, the extending arms whereof have a segment of screw thread cut therein. The thread in the arms of the spider engages the thread 19 in the nozzle 17. In this form of the invention, the pad 12 is secured directly to the solid 90 center 25 of the spider 24.

The modified form of the invention is found desirable when the body of the nozzle is elongated to permit variable extension of the nozzle and of the working length of the 95 nozzle. It is obvious that the spider 24 may be inserted in the barrel of the nozzle 17 and arrested at any point within the threaded body thereof.

To avoid leakage of water between the barrel of the nozzle 17 and the head 10, a packing ring 26 is provided, the ring 26 being laid in a circular groove formed in the head 10. The ring 26 is constructed of any suitable and preferably soft material so that 105 the thread of the nozzle 17 readily compresses the ring and seals the joint between the head and nozzle.

Claims.

1. A faucet as characterized comprising an externally-threaded head having a deliv-

ery channel therethrough and provided with a flat valve seat extending throughout in a plane perpendicular to the axis of said channel at the delivery end thereof; a nozzle having a delivery passage and an internally-threaded body portion, the threads whereof register with the threads on said head; a bridge removably mounted in fixed relation to said nozzle to provide openings 5 thereunder communicating with said delivery passage and the chamber of said body portion; a yielding cushion mounted on said bridge to rest on said seat; means for holding said cushion on said bridge; and a packing ring permanently mounted on said head in the threaded portion thereof, said ring 10 being adapted for compression by the thread 15

of the body portion of said nozzle for sealing the joint between said body portion and said head.

2. A faucet of the character described comprising an externally threaded head having a delivery channel and provided with a valve seat at the delivery end thereof, a nozzle having a valve head coöperating with said seat, a delivery passage, and an internally threaded chambered body portion screwing on the head, and a packing ring mounted on said head in the threaded portion thereof, said ring being adapted for compression by the thread of the body portion of said nozzle for sealing the joint between said body portion and head.

CHARLES WIRTZ WAGNER.
